ABSTRACT OF THE DISCLOSURE

A back reflector structure particularly useful for heat sealing reed switches and the like which causes maximum concentration of radiant energy on the work unit with minimum escape or loss of useful energy. The reflector structure includes a built-in nozzle means to substantially eliminate condensing of metal oxide deposits on the independently laterally adjustable polished spherical reflector faces and the structure allows placement of the work unit at an advantageously spaced point from the back reflector parts without significant energy loss.

Background of the invention

The invention pertains to that form of device known as a back reflector, used in conjunction with a source of radiant energy, such as an infrared lamp, for delivering the energy to an object to be heated such as the glass envelope of a magnetic reed switch or the like. In such work, the problem is to collect and concentrate the energy on the object as when sealing glass to a metal part, and evenly distributing the radiation as completely as possible around the entire circumference of the object.

While the back reflector technique is well known in the art, broadly speaking, serious deficiencies have been present with known types of back reflectors and known techniques. The most serious problem encountered in the prior art arises from the utilization of a one-piece cylindrically curved back reflector in conjunction with a frontal radiant energy source. The object to be heated, such as a reed switch envelope, is typically smaller than the focal zone of the radiation produced and as a result substantial portions of the energy zone lie outside of the glass element and are therefore unusable. To offset this, it is necessary to bring the back reflector relatively close to the object being heated, and this gives rise to another major problem or defect, namely, the formation of objectionable oxide deposits from the glass on the highly polished (gold) face of the reflector.

Furthermore, a cylinder presents a flat elemental surface to the energy rays producing divergence and dilution of energy density.

Other prior art techniques involving constant rotation of the object being heated are not entirely practical and present complex problems of fixturing. Additionally, the possibilities of heating the object from two or more sides are very limited and therefore the back reflector technique is best suited to the typical situations encountered in the industry.

Summary of the invention

In accordance with the present invention, the above deficiencies of the prior art practice are substantially overcome and eliminated. The invention makes use of a split or divided back reflector which is essentially spherically curved rather than being cylindrical. This arrangement allows placement of the glass element to be heated at a point sufficiently remote from the reflector faces to minimize the tendency for oxide deposits to form on the

2

reflector faces. The invention takes advantage inherently of the gap or space between laterally separated reflector parts to totally eliminate objectionable deposits in the central area while at the same time allowing the radiant energy to be efficiently concentrated on the work unit with minimum loss and evenly around the circumference of the work unit. The supporting of the reflector sections enables the employment of an air jet for further inhibiting the condensation of oxide and other impurity deposits on the reflector faces.

Brief description of the drawing

FIGURES 1A and 1B are partly diagrammatic plan views of prior art back reflector techniques;

FIGURE 2 is a horizontal cross section of back reflector structure embodying the invention;

FIGURE 3 is a partly diagrammatic side elevation of the invention; and

FIGURE 4 is an exploded perspective view of the invention.

Description of the preferred embodiment

Referring to the drawings wherein like numerals designate like parts, attention is directed first to FIGURE 1A which graphically illustrates conventional prior art techniques. In FIGURE 1A, a radiant energy source, such as an infrared source 10, is indicated. Typically, this may be a 1000 watt tungsten filament with a suitable approximately parabolic gold reflector, not shown. A back reflector 11 is provided in the form of a cylindrically curved body whose interior surface is gold-plated. The one-piece back reflector 11 may have mounting extensions 12. The work unit 13, such as a cylindrical glass tube or envelope for a reed switch, is located inwardly of the center of curvature 14 of the back reflector 11. Typical rays 15 emanating from the energy source 10 are shown reflecting from the cylindrical surface of the back reflector at points 16 and entirely missing the glass object 13 to be heated. The radiant or heating energy zone 17 produced by the coaction of the source 10 and back reflector 11 is shown approximately and graphically in broken lines as an ellipse and it is evident in FIGURE 1A that the glass element or object 13 lies substantially outside of the zone 17 except for a relatively small segment of the zone and consequently the major part of the reflected heat energy is lost or ineffective to heat the element 13 in FIGURE 1A.

This inefficient prior art arrangement leads logically to the arrangement of FIGURE 1B, also a part of the prior art teaching. In this figure, the cylindrically curved back reflector is shown at 11' and the glass element or envelope is indicated at 13'. As is apparent in FIGURE 1B, the glass element has been moved considerably toward the reflective surface of cylindrical back reflector 11', to a point more than one-half of the radius of the back reflector closer to the reflective surface. The purpose of this adjustment is to locate the glass element totally within the confines of the radiant energy zone 17'. However, it will be noted that this compensation or adjustment gives rise to another serious problem caused by the fact that the melting glass is moved considerably closer to the back reflector, whereby metal oxide from the glass has a much greater tendency to condense as a dull gray coating 18 on the reflecting surface, thus destroying its usefulness. Therefore, while the arrangement of FIGURE 1B increases the efficiency of the system from the standpoint of utilizing more of the available heat energy from the zone 17', simultaneously a new and equally serious problem arises due to placing the glass element too close to the reflective surface and thus encouraging the formation of the metal oxide deposit 18 thereon. Also, it may be observed in FIGURE 1B that large end portions 19 of the

energy zone 17' are still well outside of the space occupied by the element 13' and this energy is thus lost or ineffective to heat the element 13'.

FIGURES 2-4 inclusive show the invention structure which to a great extent overcomes the difficulties which have been discussed in connection with FIGURES 1A and 1B.

Referring to FIGURE 4, a mounting bracket or holder 20 is shown including a vertical body portion 21 which may be attached to a suitable structural element of a reed switch fabricating apparatus or the like. The holder 20 further comprises back reflector support arms 22 and 23 which are spaced apart laterally, there being a connecting web 24 between these arms, as shown. Spherically curved back reflector sections 25 and 26 are provided and these sections are spherically curved in both the vertical and horizontal planes. Each reflector section has an end lateral mounting extension or tab 27 having an adjusting slot 28. The extremities of support arms 22 and 23 have machined grooves 29 which receive the tabs 27 and screws 30 serve to adjustably rigidly secure the back reflector sections to the support arms 22 and 23 in desired laterally adjusted positions permitted by the elongated slots 28.

There will always be a gap or space 31 between reflector sections 25 and 26 and thus it is impossible for the mentioned oxide deposits to accumulate in this region. To further inhibit the formation of the deposits on any part of the reflective surface, a forwardly directed jet of air is caused to flow through the gap 31 from a small nozzle or tube 32 connected within an opening of the web 24. The entire holder 20 may be rendered vertically adjustable upon its primary support so that the back reflector sections can be adjusted in two planes. The reflective faces of sections 25 and 26 are gold-plated with a highly polished finish for maximum efficiency.

FIGURES 2 and 3 show in a somewhat diagrammatic form the advantages of the invention structure in comparison to the prior art. In FIGURE 2, the infrared source or lamp is indicated at 33 and the cylindrical glass envelope at 34. The radiant energy zone 35, as shown in FIGURE 2, is considerably foreshortened due to the separated arrangement of the back reflector sections and the glass envelope may be centered within the zone 35 and spaced sufficiently far from the spherical reflective surfaces so that there will be no serious tendency to cause an oxide formation thereon. The gap or space 31 immediately behind the glass envelope eliminates the oxide coating problem in the most critical area and, as stated, the air stream from the tube 32 continually flowing forwardly through this gap tends to direct any particles of oxide or impurities away from the reflective surfaces.

It may be observed in FIGURE 2 that the axial center of the glass envelope may be positioned considerably less than one-half the radius of a reflector section inwardly of the centers 36, these centers 36 being the true centers of curvature in the horizontal plane of spherically curved back reflector sections 25 and 26. Each such reflector section also has a center of curvature 37 in the vertical plane as shown in FIGURE 3. Continuing to refer to FIGURE 2, the centers 36 are spaced equidistantly laterally of a center line 38 through the center of the gap 31. A radius for a single spherically curved back reflector would lie on the center line 38. However, a significant feature of the present invention resides in spacing the centers 36 equidistantly on opposite sides of the center line 38 so that energy rays 39 from the source 33 will be reflected from points 40 on spaced reflector sections 25 and 26 back onto the glass envelope 34, rather than wide of the same as in FIGURE 1A. As a result of the invention arrangement, the heat energy zone 35 is much less elongated and much less of the available heat energy is lost or unused on opposite sides of the envelope 44 as graphically illustrated in FIGURE 2. Consequently, the geometry of the parts in FIGURE 2 is such that the 75

heating of the glass element 34 efficiently and uniformly around its circumference is greatly increased and the tendency for oxide deposits to condense on the spherical reflected surface is greatly decreased, thus satisfying the two main objectives of the invention.

FIGURE 3 depicts graphically the advantage gained by having each reflector section curved in the vertical plane, as contrasted to the straight cylindrical back reflector 11' of the prior art. In FIGURE 3, an incoming energy ray 41 is reflected at 42 from back reflector 11' and misses entirely the glass envelope 34 as indicated at 43. However, the same ray 41 reflected at 44 from the spherical reflector section 25 passes directly onto the upper portion of the glass envelope as indicated at 45, for example, as during the forming of the upper glass seal of a reed switch or like device.

In this connection, it should be understood that the reflector sections 25 and 26 may be employed in upper and lower pairs in a reed switch fabricating apparatus so as to be capable of producing upper and lower glass seals on each switch in cooperation with a vertically shifting radiant energy source.

The spherical shape in the vertical plane of reflector sections 25 and 26 may not represent the ideal curvature, but this construction renders fabrication of the back reflector much simpler since the horizontal curvature is circular. The spherical configuration satisfies the requirements or criteria for the invention very nicely. The light pattern is strongly divergent as it leaves the glass seal area. This light or energy must be collected and returned to the seal area in a convergent pattern or otherwise the energy density is diluted and the pattern is wider on the back side than on the front.

Essentially, the invention structure has accomplished the following. The light path or energy path is directional and the pattern is rapidly converging and diverging as it enters and leaves the focal zone 17-35. The energy rays falling outside of the glass object in simple terms totally misses the target. As previously mentioned, there are two end zones of energy that are available for further work but are ordinarily wasted; the outer ends 19 of the focal zone that have missed the glass, the center portion of the zone having been absorbed by the glass on the first pass of the rays and therefore unavailable for further work. In order to manipulate these two potential energy sources and direct them to the rear portion of the glass seal, concave optics is employed by the invention to collect the divergent rays and cause them to converge on the seal area. Since there are two separated zones of energy as described, the concave optics is divided in the invention to handle both zones properly. It is believed that in view of the drawings and the above description, the advantages of the invention over the prior art will now be readily apparent to those skilled in the art without the necessity for any further description.

I claim:

1. A back reflector structure for heat sealing glass envelopes of reed switches and the like in cooperation with a radiant energy source spaced forwardly of the glass envelope, said structure comprising a supporting bracket including a pair of laterally spaced arms and an intermediate connecting portion, a pair of separately formed approximately spherically curved back reflector elements having forward concave reflecting surfaces and arranged rearwardly of the glass envelope to be sealed, means for adjustably securing each back reflector element to one of said arms so that each back reflector element is rendered independently adjustable laterally relative to the other element to establish a central gap of desired width between the back reflector elements, and a fluid nozzle connected in said intermediate portion of the supporting bracket for directing a fluid jet forwardly through said gap to inhibit and retard the formation of oxide deposits on said concave reflecting surfaces.

2. A back reflector structure as defined by claim 1,

wherein said means for adjustably securing comprises a slotted extension carried by each back reflector element, a guiding edge portion on each arm of the supporting bracket engageable with one of said extensions, and a clamping fastener element for each back reflector element engageable through the slot of said extension and being engaged with one of said arms of the supporting bracket.

3. A back reflector structure as defined by claim 1, wherein said means for adjustably securing comprises a guide groove in the forward end of each bracket arm, a lateral extension on the outer forward end of each back reflector element and being slidably engageable within one of said grooves and having a slot formed therethrough, and a threaded fastener element engaging through each slot and having screw-threaded engagement with one of said arms.

4. A back reflector structure for use in conjunction with a frontal source of radiant energy for heat sealing a glass envelope of a reed switch or the like located between said frontal source and structure, said structure comprising a unitary supporting racket adapted to be secured to a reed switch fabricating unit and including a pair of laterally spaced arms and an intermediate portion connecting said arms adjacent the rear ends of the arms, a central forwardly opening fluid nozzle device connected

5

10

15

20

25

with said intermediate portion substantially midway between said arms, and a pair of back reflector elements having forward approximately spherically curved concave reflecting surfaces and lateral mounting extensions engageable with the forward ends of said arms, and means to clamp said extensions adjustably to the forward ends of said arms and enabling each back reflector element to be independently adjusted laterally relative to the flow axis of the nozzle device.

5. A back reflector structure as defined by claim 4, and a lateral guide surface on each arm slidably engaging one of said extensions.
